UNITED STATES PATENT OFFICE.

HERMAN STAPELMANN AND JULIUS JUCH, OF NEWARK, OHIO.

VITREOUS FURNACE.

1,170,575.

Specification of Letters Patent.

Patented Feb. 8, 1916.

Application filed July 22, 1914. Serial No. 852,499.

To all whom it may concern:

Be it known that we, HERMAN STAPELMANN and JULIUS JUCH, citizens of the United States, residing at Newark, in the county of Licking and State of Ohio, have invented certain new and useful Improvements in Vitreous Furnaces, of which the following is a specification, reference being had to the accompanying drawings.

10 This invention relates to furnaces and the like for the manufacture of vitreous compositions, and more in particular to means for drawing off the same in their molten state.

15 One of the objects of this invention is to provide means for a furnace which will permit molten material from the same to be drawn off in a clean stream, and without scum mixed therewith.

20 A further object is to provide such means with an arrangement for permitting it to be readily inserted into a furnace, and into molten material, and in such a way that the most desirable part of the material will tend 25 to flow into the spout.

Another object is to provide such means, with end portions which will be especially designed to prevent the ingress of undesirable material into the spout.

30 Other objects will become apparent as the invention is more fully set forth.

In the appended drawings which show a modification of this invention: Figure 1 is a perspective phantom view of an embodiment 35 of this invention. Fig. 2 is a longitudinal sectional view of the embodiment. Fig. 3 is a plan view of the embodiment. Figs. 4 and 5 are transverse sectional views.

Similar reference characters refer to similar parts throughout the drawings.

In the construction shown, the reference character 1 represents the wall of a furnace which is provided with an opening 2 for a spout 3. The spout is provided with a 45 groove or channel 4 near its upper portion as is clearly indicated in the drawings, and this channel is preferably rounded and restricted at its bottom. The channel runs longitudinally through the spout or spout

block, as it may be termed, and runs through 50 to one end, the drawing-off end, but stops some appreciable distance from the other or furnace end.

A passage 5, transversely and downwardly extending through the block, connects the 55 channel with the bottom of the block. The block is of such dimensions that its upper surface will be above the level of the molten material in the furnace. In this way the molten material can only flow out through 60 the spout by following a path to the bottom of the block, thence up through the passage 5, thence along the channel 4 and out of the open end 6 of the same.

It will be noted that only the cleaner 65 molten material will go into the spout, the scum being prevented from doing so by reason of its being on the upper surface of the fluid, and the sludge being settled on the bottom of the furnace. Thus the flow 70 in the spout will be always clean and that taken out will be more satisfactory than without such an arrangement. The channel portion over the passage being in the furnace the fluid therein will be kept hot and 75 with an even pressure upon it.

While but one form of the invention is shown in the drawing it is not desired to limit it to that particular form or in any other way otherwise than limited by the 80 prior art, as many other constructions can be made without departing from the principles of this invention and coming within the scope of the appended claim.

We claim:

85 In combination with a furnace having a rectangular opening, a rectangular prismatic spout block insertible in and filling the opening, said spout having a longitudinally grooved open duct in its upper surface portion and extending from the outer end of the block to a point away from the inner end of the block, said duct having its lower portion or depth arranged below the normal level of the material melted in the furnace, 90 and its upper and open portion above and accessible to inspection, a duct through the block extending from the inner end portion

of the groove duct to a point below the scum line of the material in the furnace, said ducts being disposed in the block where-
5 by the flow of molten material through the same may be controlled by moving the block horizontally in the opening.

In testimony whereof we hereunto affix

our signatures in the presence of two wit-
nesses.

HERMAN STAPELMANN.
JULIUS JUCH.
